GARAGE DOOR

Wesley A. Smith, Detroit, Mich.

Application June 25, 1934, Serial No. 732,260

6 Claims. (CL 20—16)

This invention relates to doors for garages or other buildings having openings through which persons and vehicles are to pass, the object being to provide a one-piece door rotatable near its upper end about a horizontal axis and that is so hung in relation to the weighted upper end that the door assembly is in a state of balance in a partially open position whereby upon initial manual movement toward either the open or closed position, the door is moved automatically by gravity to complete the closing or opening movement.

An additional feature and object of the invention is to provide a releasable lock element to securely hold the door in open position in a substantially horizontal plane for automatically locking the door on movement to closed position.

An object and feature of this invention is to provide a door which is adjustable laterally of the door opening to enable the same to be centered and vertically adjustable also to properly position the door in relation to the top cross member of the opening and to the floor line or bottom of the opening.

An additional object and feature of the invention is to provide a yieldable element at the lower edge of the door to compensate for variations in the floor surface subsequent to installation of the door. The adjusting feature for positioning the door is in the nature of a trunnion which, in the event of a settling of one side or the other of the door, enables the door to be squared in relationship thereto in conjunction with which are provided stop or filler strips at each vertical edge of the door and extending into the opening of the door frame against which the door closes.

It is further an object and feature of the invention to provide a door of sheet metal construction of sufficient strength for the purpose carrying at its upper end a sheet metal housing filled with material to provide a counterbalancing weight for the door above the trunnions practically equivalent or equal to the weight of the door portion below the trunnions.

These and other objects and various novel features of the invention are hereinafter more fully described and claimed, and the preferred form of construction of a door embodying my invention and a framed opening therefor is shown in the accompanying drawings in which—

Fig. 1 is an elevation of the door from the inside.

Fig. 2 is a section of the door taken on line 2—2 of Fig. 1.

Fig. 3 is a side elevation of the trunnion taken on line 3—3 of Fig. 1.

Fig. 4 is a section through the door and latch element for locking the door in closed position taken on line 4—4 of Fig. 1.

Fig. 5 is a vertical section through the door taken on line 5—5 of Fig. 1 showing the door in the closed position.

Fig. 6 is a similar view showing the door in open position and the locking means for holding the same in the open position.

Fig. 7 is a similar view showing the locking means in released position.

As shown in Fig. 1, the opening for the door has the vertical sides 1 and 2 and a top rail 3, 15 the rail 1 being shown in cross section in Fig. 4. Each vertical rail or stile of the frame has a filler bar 4 attached thereto and extending into the opening and against which the door member having the metal face seats. The door has a 20 flange 6 at each vertical edge engaging against the outer face of the filler members 4. The door proper is preferably made of comparatively thin sheet metal having the V shaped ribs 7 therein to strengthen the same against deformation in 25 its longitudinal plane. Bars or channels 8, 9, 10 and 11 are provided across the inner face of the door to support the same against transverse deformation. The side edges of the door are provided by Z shaped bars 12 which are of 30 greater width at the top than at the bottom as will be understood from Fig. 5 and on the exterior face of these bars and channels is the sheet metal door surface 5, it being inturned about a flange of each of the side bars 12 as 35 will be understood from Fig. 4. The upper end of the door is formed by the hollow metal member 13 secured by bolts 14 to the Z bars 12. This member may be filled with a cement 15 into which the upper edge of the sheet metal 5 40 may extend as shown in Fig. 5.

The door is supported by trunnions indicated generally at 16 in Figs. 1 and 3. These trunnions consist of a U shaped bar 17 which is bolted to the door frame and a bolt 18 passes 45 through the free end of one leg of the U and through the other leg into the member 4 subsequent to positioning the supporting member 19 in place. The member 19 is of cylindrical form and flanged at its opposite ends as indicated at 50 20 to engage opposite edges of the U member to prevent longitudinal displacement. Through this member on each side of the door extends a threaded bolt 21 in each case and on these two bolts the door is supported, there being a bracket 55

22 on each side of the door attached to the cross bar 10 and having an eye 23 at its outer end shown in Fig. 2 which is slotted at 24 to receive the bolt. On opposite sides of the eye is a nut 5 25 and 26 on the bolt by which the eye is clamped in place, the eye permitting vertical adjustment of the door relative to the opening and to the trunnions. The supporting member 19 is vertically adjustable in the U member 17 10 and is supported by a vertical bolt 27 having a lock nut 28 thereon and thus variation in position of the bolt 21 in the eye piece and variation of the bolt 27 in the U member permits of the necessary vertical adjustment of the door 15 relative to the opening. The adjustment of the bolt 21 in the eye 23 enables the door to balance in practically half open position as such adjustment permits moving the weighted end of the door nearer to or farther from the pivot point. 20 Also, these bolts 21 of the trunnions permit lateral adjustment of the door relative to the opening by variation in position of the nuts 25 and 26 therein so that the door may be centered between the frames 1 and 2 and with the flange 6 25 overlying the filler strips 4 as shown in Fig. 4.

The metal portion 5 of the door does not extend to the floor line 29 shown in Fig. 1 and to fill this space between the bottom edge of the metal portion of the door and the floor line 29, 30 I provide a flexible strip 30 which may be of rubber and canvas or other appropriate material and this is secured to the lower edge of the door by bolts extending through a bar 31, the flexible member 30 and the bottom edge of the sheet metal portion 5 of the door. By this means any variation in the level of the floor subsequent to installation of the door, which is usually of cement as indicated in Fig. 5, does not cause the door to stick or to be distorted by pressure as 35 the flexible element will conform to limited variation in the floor surface.

The major feature of the invention resides in the provision of a door turnable on a horizontal axis near the upper end and at a height from the 40 floor line to permit an ordinary passenger automobile or person to pass beneath the door when in the horizontal position and in so weighting the door that when released from its closed position, it will balance at an angle to the vertical 45 as indicated by the dotted line *a* in Fig. 5 and in association with the door of a means for automatically locking it in the full open position against displacement. This locking means comprises a lever 32 pivotally supported at its upper 50 end to any convenient part of the building structure here shown as a rafter 33 and has a series of apertures 34 therein intermediate its ends.

The lower end 35 of the bar 32 is offset as 55 shown clearly in Figs. 5 and 6 and a pair of bars 60 37 and 38 are pivoted at one end to the bar 32 at one of the apertures 34 and at the opposite end are pivoted at 39 to ears 40 provided at the upper edge of the casing 13. These ears are preferably formed of a bar extending into the 65 cement and projecting from the upper edge of the casing 13 holding the cement. Thus the lever 32 lies between the arms 37 and 38 as shown in Fig. 1 and the offset end 35 engages against the free end of a releasing latch 41 70 pivoted on the bolt extending through the ears 40 and bars 37 and 38. When the door is opened and turned on its pivotal support from the position shown in Fig. 5 to the position shown in Fig. 6, the bars 37, 38 and 32 are folded together 75 and the point 34 of connection of the levers 37

and 38 to the bar 32 lies inside a line passing from the pivot point 39 to the pivot point of the bar 32 in its bracket on the rafter 33. Thus when the parts are in the position shown in Fig. 6, any weight or wind pressure applied to the outer free end of the door tends to press the pivot point between the bars 37, 38 and 32 in the direction of the arrow in Fig. 6 and this forces the end 35 of the bar 32 tightly in contact with the latch member 41 and prevents movement of the pivot point 34 of these bars and will sustain any weight or pressure short of such weight as would deform the parts. If now it is desired to release the door from the full open position, the latch member 41 is operated in the manner indicated in Fig. 7 to move the end 35 of the lever 32 outwardly of the door and moving the pivot point 34 in the direction of the arrow in Fig. 7 permitting the door to turn by its own weight on its horizontal axis.

The latch 41 may be operated by a cord 42 shown in Fig. 7 as attached to the short end of the pivoted latch 41 and a pull on this cord turns the latch as shown in Fig. 7 to release the locking or holding mechanism. This release may also be accomplished by a cord 43 shown in Figs. 5 and 6, it being attached to the offset end 35 of the lever 32 extending over a pulley 44 supported in the building structure and the cord may then pass out of the building to the house for instance and a pull thereon will release the door to swing by its own weight on the pivot. This cord 43 may of course run to any convenient point within reach of the operator when the door is open and when used the releasing latch 41 may be dispensed with.

Upon closing the door it is desired that it be locked and a convenient means of locking the door in the closed position and that will automatically lock in swinging the door to closed 40 position consists of the latch 45 shown in Fig. 4 and slidable in the casing provided therefor by means of a handle 46 on the exterior of the door having a lever 47 engaging in an aperture provided in a rearwardly extending portion 48 of 45 the latch which is to be understood as being spring-pressed to the position shown in Fig. 4. Thus to open the door this latch member must first be withdrawn from the locking position shown and while not so shown, this may be a 50 key-operated structure. Preferably, upon the filler member 4 is provided a strike plate 49 which, on the closing movement of the door in the direction of the arrow shown in Fig. 4, the inclined face of the latch 45 engages the strike 55 plate and when the door comes to closed position engages behind the strike plate.

Thus, it will be seen from the foregoing description that by using ribbed sheet metal and a stiffening framework, a door comparatively light 60 in weight is secured and yet of sufficient strength to efficiently serve its purpose. The door is also vertically and laterally adjustable to properly position the same in the framed opening provided therefor and by means of the slotted ears 65 23 the point at which the door will balance in practically open position, as indicated by the dotted line *a* in Fig. 5, may be determined. When so balanced the door may be initially started to swing upon its horizontal pivot, either 70 to open or closed position and thereafter, due to the counter-balancing of the door by the weighted end above the pivot point, movement to the full open or closed position is completed by gravity and the door is automatically locked 75

in such position against accidental displacement.

It is further pointed out that the invention is not confined to a door formed of metal as a door or barrier of any desired or commonly used material for door constructions may be utilized and various departures made from the specific construction shown as fall within the spirit and scope of the appended claims.

It will also be observed that the various objects of the invention are attained by the construction described.

Having thus fully described my invention, its utility and mode of operation, what I claim and desire to secure by Letters Patent of the United States is—

1. The combination with a framed opening of a building having vertical stiles, a top and a bottom, of a door for closing the opening, means for supporting the door to turn on a horizontal axis, a counter-balancing weight for the door, means for adjusting the door laterally of the axis to center the same between the vertical sides of the opening, means for adjusting the door transversely of its horizontal axis whereby the center of gravity of the weighted door passes approximately through the axis when the door is in a partially open position and enabling the door to automatically move by action of gravity to a fully closed or a fully open position upon displacement in one direction or another from its balanced position and a flexible element forming the lower edge of the door and engaging the bottom.

2. The combination with a framed opening in a vertical wall of a building, of a door supported therein and turnable about a horizontal axis near its upper end to horizontal open position or vertical closed position, a counter-balancing weight extending across the upper end of the door and fixed to the upper edge thereof in position to balance the door at an angle to the vertical, means for adjusting the door transversely of the pivot point to thereby adjust the position of the door to balance in partially open position, a releasable latching means for holding the door in the closed position, and means for automatically locking the door from movement on its axis when turned to full open horizontal position.

3. The combination with the framed opening in a vertical wall of a building, of a door for closing the same, means for supporting the door to swing on a horizontal axis adjacent its upper end, a weight at the upper end of the door, means for adjusting the axis of rotation whereby the weight is so positioned that the door is in a state of balance in a partially open position and as the door is swung in either direction past the plane of balance by manual force the door automatical-

ly swings to a fully open or fully closed position respectively, means automatically locking the door when moved to full open horizontal position, said last named means including a toggle arrangement in which the pivot point is moved to one side of a neutral position, and means for actuating the leverage device to move the pivot point to the opposite side and thereby permit the toggle to fold and enable the door to be closed.

4. The combination with a framed opening of a door of less width than the width of the opening, filler strips at each vertical edge of the door opening against which the door may close, said door comprising longitudinal side bars each having an outwardly extending flange, a sheet metal cover member for the side frames inturned over the said flanges, the flanges, when the door is closed, seating against the filler strips, a bracing means to support the side frames and sheet metal member, said sheet metal member having longitudinally extending grooves formed therein to brace the metal against bending longitudinally, a horizontal pivotal support for the door adjacent its upper end on which the door may turn, said pivotal support comprising a bracket secured to each vertical side of the door frame, a bolt secured to the door, a cylindrical member through which the bolt extends, said bracket supporting the said member from movement horizontally, and means on the bracket for vertically adjusting the position of the cylindrical member.

5. The combination with a framed opening of a building, of a door for closing the opening, means for supporting the door to turn on a horizontal axis, a counter-balancing weight on the door above the axis, means for adjusting the door transversely of the axis to so position the weighted door that the center of gravity passes approximately through the axis to balance the door in a partially open position thereby providing a door that will automatically move by gravity to fully open or closed position upon displacement to one respective side or the other of the plane of balance.

6. The combination with a framed opening in a vertical plane, of a door for closing the opening, means for supporting the door to turn on a horizontal axis above its transverse center plane, a counter-balancing weight on the upper end of the door so positioned relative to the horizontal axis as to cause the center of gravity to pass approximately through said axis to balance the door in a partially open position and to automatically cause the door to move from said partially open position to fully closed position when moved in a corresponding direction from said point of balance.

WESLEY A. SMITH.
